E. H. OWSLEY.
TROLLEY ACTUATED SWITCH.
APPLICATION FILED OCT. 19, 1914.

1,153,515.

Patented Sept. 14, 1915.

UNITED STATES PATENT OFFICE.

EDGAR H. OWSLEY, OF SAN JOSE, CALIFORNIA.

TROLLEY-ACTUATED SWITCH.

1,153,515.

Specification of Letters Patent. Patented Sept. 14, 1915.

Application filed October 19, 1914. Serial No. 867,369.

To all whom it may concern:

Be it known that I, EDGAR H. OWSLEY, a citizen of the United States, residing at San Jose, in the county of Santa Clara and State of California, have invented new and useful Improvements in Trolley-Actuated Switches, of which the following is a specification.

This invention relates to trolley actuated switches and the object thereof is to provide an improved form of switch which is of simple construction and which is capable of easy and quick operation by the trolley.

The invention consists of the parts and the construction and combination of parts as hereinafter more fully described and claimed, having reference to the accompanying drawings, in which—

Figure 1 shows a modified form of switch operating mechanism. Fig. 2 is a side elevation of the preferred form of switch operating mechanism. Fig. 3 is a cross section through the separated chambers of the four-point double switch. Fig. 4 is a perspective view of the switch and connected operating mechanism. Fig. 5 is a slight modification of the structure shown in Fig. 2.

The switches are double in arrangement, i. e., two knife blades 9 and 10 are secured on shaft 8 and a double set of contacts 11—12 and 11^a—12^a are provided for purposes hereinafter to be described. Each double switch is suitably supported, with relation to the trolley wire hanger, as indicated at 5, Fig. 4, and consists of a casing which is divided into two separated compartments 6 and 7 through which extends the shaft 8. The knife switch blades 9 and 10 are secured on the outer ends of the shaft, as indicated in Fig. 3, one in each chamber 6 and 7, and are adapted to be thrown into engagement with their respective contacts 11—12 and 11^a—12^a by means of a centrally disposed arm 13 and an operating mechanism hereinafter to be described. Arm 13 is loosely mounted on shaft 8 and is provided with a pawl 14 on its inner end which is adapted to engage with a ratchet wheel 15 secured upon the shaft.

Pivotaly mounted in a bracket bearing

16, secured on the outside of the switch casing, is a lever arm 17, the lower end of which is connected with an arm 13 by means of a link 18. Pivotally mounted, as at 19, on a bearing member 20 carried by the trolley wire 21 is a block 22. Extending upwardly from said block is an arm 23 which is connected with the arm 17 by means of a link 24.

Pivotally secured, as at 25, to the lower end of a block 22, one one side, is a horizontally disposed link or block 26, the other end of which is slidably mounted, as at 27, in a standard 28 carried by the trolley wire. Block 22, together with the link 26, is adapted to be raised into the vertical position indicated in Fig. 4 by engagement with the trolley wheel 29 of a passing car for the purpose of rocking the connected levers 23, 17 and 13, which movement is transmitted through the pawl and ratchet 14 and 15 to turn the shaft 8 and swing the knife blades 9 and 10 out of engagement with one contact and into engagement with another contact. The connected levers 13, 17 and 23 and blocks 22 and 26 will return to the normal tilted position indicated in Fig. 2 the moment the trolley wheel passes by, as the weight of block 22, together with that of the connected link or block 26, is sufficient to swing the levers back. Pawl 14 will be inoperative at this time as it simply slips over the teeth of the ratchet wheel. The shaft 8 will thus remain stationary on the return movement of the levers and will not turn until the connected blocks 22 and 26 are raised by engagement with the trolley wheel. The block 22, with connected block or link 26, is a little wider than the face of the trolley wheel and will thus become positively raised by same when the trolley wheel passes thereunder.

The chambers in the respective switches are preferably filled with oil to prevent flashing or burning away of the contact points as the switches are opened or closed, and stand-pipes 29^a, projecting through the top of the casing, are preferably provided for filling the respective chambers. The oil contained in the chambers may also be used for lubrication.

As shown in Fig. 3, a valve control drip pipe 30 is provided, by means of which lever 13 may be automatically lubricated. Levers 17 and 26 are similarly provided with oil ducts, such as indicated by dotted lines at 31, through which the several pivot bearings and link connections may be lubricated.

The car may run in either direction or 10 may turn back at any point when a system of the character described is employed, as the switch operating mechanism, consisting of the blocks 22 and 26, permits a rocking movement by engagement with the trolley 15 wheel whether this is passing in one direction or the other. The rocking movement transmitted through levers 23, 17 and 13, when rocked by blocks 22 and 26, swings the arm of lever 13 a quarter of a revolution and 20 consequently moves the shaft 8 sufficiently far to turn the knife blades from one contact into another.

The shafts 8, upon which the knife blades are mounted, will always turn in the direction of arrows *c* whether the car be traveling along the track in one direction or the other, as lever 13 and pawl 14 will only turn the shaft when the levers are moved into the vertical position shown in Fig. 5.

30 In Fig. 1 a slight modification of the switch operating mechanism is shown. The block here indicated is provided with one or more downwardly extending arms 40 which are adapted to be engaged by a pin 41 on the trolley pole fork. The passing of the trolley in one direction will swing the block, with connected arms 40, to one side and throw the switch, while the reverse movement of the car will rock it in the opposite 40 direction.

The materials and finish of the several parts of the signal system are such as the experience and judgment of the manufacturer may dictate.

45 I wish it understood that various changes in form, proportions and minor details of construction may be resorted to within the scope of the appended claims and that I do not wish to limit myself to the specific design and construction here shown.

In Fig. 5 block 22 is shown as provided with an extension 22^a with which link 26 is connected. This structure is used in connection with flat trolley wheels such as are used 55 on trolley harps and the like, it being necessary in such cases to bring the point of contact below the trolley wire, as indicated at 45.

Having thus described my invention, what 60 I claim and desire to secure by Letters Patent is—

1. In a multiple switch, a shaft extending through each switch, a knife blade for each switch on the shaft, a block pivotally mount-

ed above a trolley wire, a link pivotally connected to one end of said block and slidably mounted at the other end in a standard, said block and link being so positioned as to be rocked when engaged by a trolley wheel of a passing car, means connecting the block with the switch shaft whereby the rocking movement of the block and link will be transmitted to turn the shaft with connected knife blade a quarter of a revolution from one contact in the switch to the other, a casing inclosing each switch and in which each shaft is journaled, means for introducing oil into said casing, and means for conveying a portion of said oil to lubricate the shaft with connected operating levers.

2. In combination with the blade of a switch, a pivoted block, a link pivoted at its inner end to the block adjacent the base of the latter whereby the under faces of the block and link conjointly have a V-shape 75 form, means to pivotally support the outer end of the link, an arm extending upwardly from the block, an arm having connection with the switch blade to actuate the latter, a lever arm pivoted intermediate its ends, 90 and links connecting the ends of the lever arm with the arm of the block and the arm of the switch blade.

3. In combination with the blade of a switch, an arm having connection with the 95 blade to actuate the latter, a vertical lever arm pivoted intermediate its ends, a link between the lower ends of the first named arm and the lever arm, a vertical pivoted member for actuation by a trolley wheel or 100 the like, and a link between the upper end of said member and the upper end of the lever arm.

4. In combination with a switch actuator, a vertical pivoted weighted substantially L-shaped member having the free end of its 105 base disposed below its pivot so as to be engageable with a trolley wheel or the like whereby to rock the member, and means connecting the member and actuator whereby 110 the member will operate the actuator.

5. In combination with a switch actuator, a vertically rocking substantially L-shaped member having the free end of its base disposed so as to be engageable with a trolley 115 wheel whereby to rock the member, said member being pivoted at its corner so as to be automatically returned to normal upon the trolley wheel passing out of contact with same, and means to operate the actuator 120 from said member.

6. In combination with a switch actuator, a vertically rocking substantially L-shaped member having the free end of its base disposed so as to be engageable with a trolley 125 wheel whereby to rock the member, said member being pivoted at its corner so as to be automatically returned to normal upon

the trolley wheel passing out of contact with same, means to operate the actuator from said member, and a link slidably supported at one end having its other end pivoted to 5 the free end of the base of the member.

7. In a switch, a casing having an oil containing compartment, a switch blade in the compartment, means located exteriorly of the compartment and connected to the blade 10 to operate the latter, and means leading

from the compartment and communicating with the oil therein for lubricating the blade operating means.

In testimony whereof I have hereunto set my hand in the presence of two subscribing 15 witnesses.

EDGAR H. OWSLEY.
